AUTOMATIC VACUUM CLEANER

Leon P. Borkoski, Stamford, Conn., assignor to
 Electrolux Corporation, New York, N. Y., a corporation of Delaware

Application May 4, 1951, Serial No. 224,575

10 Claims. (Cl. 183—51)

1.

This invention relates to a vacuum or suction type cleaner having automatic controls. More particularly, it embraces an automatically conditioned tank type cleaner having self-contained control mechanisms for removing accumulated dirt in packaged form, readied for immediate disposal. With this cleaner the dirt entrained in the incoming air suction stream is collected in a porous disposable bag located within the cleaner and, when the collected dirt effects a predetermined change in the operating efficiency of the cleaner, the latter automatically shuts itself off and disposes of the dirt-filled bag by ejecting the latter from the cleaner.

It is a major object of this invention to provide a new and improved vacuum cleaner having automatic means for disposing of dust and dirt by ejecting from the cleaner a self-sealing porous and disposable paper bag filled with dust and dirt separated from the suction air stream during normal operation of the cleaner, utilizing a simplified mechanical release means to effect the necessary steps.

It is a further and important object hereof to provide automatically positioned toggle means for presetting a releasing device to operating condition.

A still further object of this invention is to provide a device which avoids the inconveniences present in the conventional suction type of vacuum cleaning device using the customary cloth or paper dust bag which periodically necessitates indiscriminate removal or replacement in order to maintain a semblance of efficient operation, such bag removal steps being heretofore effected manually and with considerable difficulty and discomfiture to the operator.

Still other and further objects will be disclosed hereinbelow or will become evident to those skilled in the art after a careful study of the following description together with the appended drawings wherein:

Figure 1 is a perspective view of the complete cleaner as seen from the air intake end, together with its conventional hose, wand and nozzle;

Figure 2 is a perspective view of a portion of the cleaner taken from a position similar to that of Fig. 1 showing the cover open, the dust bag ejector plate forward and the dust-filled bag in ejected position just prior to its coming to rest on the floor; it shows portions of the outer housing cut away in order to facilitate an understanding of the operation of the automatic mechanism;

Figure 3 is a view similar to that shown in Fig. 2 with the housing partly broken away, the

2.

cover open, the hose attached, the ejector plate pushed back and a self-sealing paper dust bag prior to its insertion into the cleaner;

Figure 4 is a vertical sectional view taken on the line 4—4 of Fig. 1, showing the ejector restraining mechanism in normal position;

Figure 5 is a vertical sectional view taken on a line similar to Fig. 4, showing the selective positioning of the triggering mechanism and in phantom the release of the front assembly;

Figure 6 is a vertical sectional view taken on a line similar to Fig. 4, showing the cover opened and in phantom the final selective position of the triggering mechanism; in full, the resetting of the triggering mechanism to substantially normal operating position is shown;

Figure 7 is a perspective view of the bag ejector mechanism of Fig. 2 in fully retracted position, taken from the rear after removal of the unit from the cleaner housing;

Figure 8 is a top plan view taken on the line 8—8 of Fig. 4 showing the electrically and pneumatically operated mechanism; and

Figure 9 is a wiring diagram including some of the pneumatic controls.

It is a feature of this invention that the functioning of the cleaner in its dust disposal capacity is automatic, self-contained and after being once initiated by the establishment of predetermined changes in the operational characteristics of the air suction stream within the cleaner, the entire sequence of operations terminating in the ejection of the dust-filled bag is effected in a series of steps. Thus, with continued dust collection during the regular operation of the cleaner, a pressure difference is gradually built up within the cleaner between the inside and the outside of the dust collecting bag. This results in a continuous and progressively increasing force being exerted upon a pressure differential measuring diaphragm, the opposite sides of which are subjected to the different pressures built up on the outside and inside of the dust bag, the chamber on one side of the diaphragm being connected to an opening communicating with the clean side of the dust bag, the chamber on the other side of the diaphragm being connected to an opening communicating with the dirty side of the dust bag. Then, upon the attainment of a predetermined value in the resultant force exerted upon the pressure differential diaphragm, motion is imparted to this diaphragm and at a predetermined distortion the diaphragm conditions means which sets into operation a series or sequence of

45 steps (electrically actuated, pneumatically actu-
 50
 55

ated, mechanically actuated, etc.,) which sequence when once initiated culminates finally in the ejection of the dust-filled bag from the cleaner housing.

In a preferred embodiment, the differential pressure diaphragm actuates a switch which closes a circuit for energizing an electromagnetically actuated armature or solenoidal unit. The armature or plunger of the electromagnetic device in turn opens a valve for admitting suction from the motor fan unit to actuate a second diaphragm which, operating through a series of linkages, (1) selectively positions a member which thereafter is in condition for subsequent operation and release of its associated ejector restraining latch; and (2) in timed relation therewith this second diaphragm substantially simultaneously, or shortly thereafter, releases a dust conveying inlet conduit from operative communication with its dust receptacle. Then, the conduit after a predetermined angular travel towards its fully released position in turn breaks a circuit cutting off the power supply to the motor fan unit. Continued travel of the conduit towards fully opened position then actuates mechanical means which moves the previously selectively positioned member the additional amount necessary to release the ejector restraining latch for actually releasing the bag ejector mechanism for dust bag ejection, whereupon the dust-filled bag is expelled from the cleaner housing and deposited upon the floor. During the dust conduit releasing steps, the timely breaking of the motor fan circuit results in a progressive deceleration of the motor speed and consequently the air suction stream also progressively decreases to a value at which highly effective bag ejection is more readily attained.

Thus in accordance with this preferred embodiment of the invention, automatic dust bag ejection is effected by mechanical means, after being initiated by a tripping mechanism including a pressure differential measuring device which actuates a responsive triggering apparatus. The pressure differential measuring device is conditioned for operation by apparatus utilizing the air pressure difference built up within the cleaner casing by dust layers collected in the dust bag. The pressure difference is established between the inside and outside of the duct collecting bag, increases progressively with continuing dust collection, and is communicated therefrom by appropriate conduit means throughout the dust collecting process.

Referring now more particularly to the drawings, vacuum cleaner housing 10, Fig. 1, is a hollow casing having a handle 11. It is appropriately supported on a pair of runners 12. The suction or inlet portion of the casing 10 is provided with an inlet nozzle 13a and wand 13b together with a suitable flexible hose 13, and connecting coupling 14 fitted into a movable hose coupling assembly 15 which is anteriorly mounted by parallel linkage including front end assembly 16. Front assembly 16, Figs. 2, 3 is hinged at 17 to front body ring 20 and biased to open position by spring 18; assembly 16 effects with casing 10 an air tight seal formed by rubber sealing ring member 19, cardboard disc 31, Fig. 3, of dust bag 30 and sealing ring 22 positioned in the bag insertion opening of front body ring 20. Tubular member 21 of the hose coupling assembly 15 extends through the opening 32, Fig. 3, cut in cardboard disc 31 well into the dust collecting receptacle 30, and is sealed against disc 75 to effect dust bag ejection. Latch bar 63 is slid-

31 by rubber sealing ring 19. Switch button 19a on the upper front surface of cleaner housing 10 provides the on-and-off manual control for the cleaner unit.

5 A perforated inner housing 23 is affixed at one end to front body ring 20 and is adapted for supporting dust bag 30 (of disposable paper or, if desired, cloth construction). This entire unit (inner housing 23, body ring 20, etc.,) is slidably 10 fitted within the open end of cleaner housing 10 and is affixed thereto by suitable retaining screws 20a. In the embodiment shown, the housing 23, reinforced by lateral stiffening plates 25 and base rods 26, is substantially rectangular in cross-section 15 and is thus adapted to take a bag of substantially similar but slightly smaller cross-section 30, Figs. 2 and 3.

Dust bag 30, Fig. 3, comprises a dust receptacle of paper or similarly air-pervious, dust-impermeable, material 33 affixed at its mouth to the 20 rear surface of a hard paper or cardboard disc 31, the latter being clamped between rubber sealing ring 19 of hose coupling assembly 15 and the open end of front body ring 20 with the aid of sealing ring 22. Cardboard disc 31 has a central opening 32 through which tubular member 21 is inserted in order to introduce the air and entrained dust directly into the interior of dust bag 30.

30 The entire inner surface of perforated inner housing or dust bag receiving compartment 23 is provided with apertures 27, Figs. 2 and 3, in order to permit suction air current to pass freely therethrough and into chamber 40. The suction air current then passes to the rear of the 35 vacuum cleaner housing 10 containing the motor fan compartment which has a conventional fan and motor unit mounted therein.

The dust bag ejector mechanism 51, Figs. 2, 3 40 and 7, for operating the bag ejector plate 52 includes a flat or leaf spring 53 which can be bowed or folded back on itself, Figs. 3 and 7, into fully flexed (loaded) condition by pushing back the ejector plate 52 into its latching position. Dust bag ejector plate 52 is hingedly attached by pin 45 54 to the front end of flat spring 53, Figs. 2 and 7, while the rear or fixed end of flat spring 53 is hingedly attached by pin 55 to rear mounting member 56. Ejector plate 52 is slidably mounted by sleeve 52a on guide rod 57 which maintains plate 52 oriented correctly throughout its region of travel. The rear wall 60 of dust bag receiving compartment 23 is affixed to the rear end of perforated inner housing 23 and has a slot 61 cut 50 therein to receive a tongue 56a which rigidly supports rear mounting member 56 of the ejector mechanism 51. Suitable bulkheads are provided within the outer housing 10 to adequately support and align inner housing member 23.

60 The ejector plate 52 of ejector mechanism 51, is held in spring loaded position by releasable latching means which engages a depending lug 52b, Figs. 2, 3 and shown more clearly in Fig. 7. Lug 52b is integral with ejector plate 52 and sleeve 52a and engages spring latch 62 when plate 52 is pushed back into loaded position, see Fig. 7. Spring latch 62 is affixed at one end to latch bar 63, and moves over a limited range therewith while simultaneously travelling down the inclined edge 56b, Figs. 2, 3 and 7, of the cam bracket portion 56c of rear mounting member 56 and, towards the end of its travel, spring latch 62 slips under the bottom edge of depending lug 52b whereupon ejector mechanism 51 is released 65 to effect dust bag ejection. Latch bar 63 is slid-

5

ably mounted on guide rod 57, at one end by sleeve 63a, Figs. 3, 4, 5 and 6; and at the other by apertured upwardly bent end portion 63b, Figs. 2, 3 and 7.

The particular details of one embodiment for a restraining mechanism adapted to control the movement of latch bar 63 is clearly shown in Figs. 4, 5 and 6 especially when considered together with Figs. 2 and 3. In these figures, latch bar restraining and releasing pin 70, Fig. 4, biased to latching position by leaf spring 70b, projects through an opening 80a cut in base plate 80. Pin 70 is adapted by downward axial movement to be withdrawn from its latch bar restraining position (Fig. 4) to its latch bar releasing position (Fig. 6).

The above latches for restraining the ejector mechanism are operated by cooperative association with appropriate selectively positionable triggering mechanism. Thus, toggle 90a, fulcrumed at 90b on lever 90 is adapted to be selectively moved to pin releasing position (see Fig. 5) by link 90c, and is held by springs 90e either in its normally ineffective position shown in Fig. 4 or in its selectively positioned pin releasing position, Fig. 5. This selective movement of toggle 90a is effected by automatic triggering initiated by pneumatically actuated means (described below and in considerably more detail in patent application Serial No. 140,894, filed January 25, 1950), and transmitted through link 90c which is actuated by arm 100a fulcrumed at 100b and linked directly to pneumatically operating triggering device 250.

Latch bar restraining and releasing pin 70 is moved to releasing position (shown in phantom in Fig. 6) by the final movement stages of the opened front end assembly 16 and/or parallel linked hose coupling assembly 15 by actuation of lever 90 through contact with the edge of assembly 16. Thus the above-mentioned selective positioning of toggle 90a results in the insertion of the forked ends 90d thereof between the spool ends 70a of latching pin 70 (see Fig. 5 and phantom view in Fig. 6). In this position lever 90 and toggle 90a will move as a unit when the edge of 16 actuates the free end of lever arm 90 to effect the downward movement of pin 70 necessary to withdraw pin 70 and release latch bar 63.

With this particular latching device for restraining the ejector mechanism 51, plate 52 is held in loaded position until assembly 16 and/or assembly 15 is practically fully released. Assembly 16 is held closed by latch 100, Figs. 2, 3, 4, 5 and 6; latch 100 is fulcrumed at 101 and biased to latching position by spring 102.

The cleaner housing 10 may be opened for inspection of the bag and its contents; however, without necessarily ejecting the dust bag by manually lifting the externally protruding end 100c of latch 100, Figs. 1, 4 and 5, thereby releasing the front end assembly 16. Then even though actuating lever arm 90 is subsequently moved by the opening of the front assembly 16 to its full extent, since toggle 90a will not have been selectively positioned (see Fig. 4), the forked ends 90d thereof will not actuate pin 70 to latch bar releasing position, therefore pin 70 will still restrain ejector 51 from discharging the dust bag. Toggle 90a thus serves as an auxiliary safety latch preventing the dust bag in either full or empty condition from being ejected upon merely manually opening the front assembly 16. On the other hand, with the front assembly 16 closed, spring latch 62 cannot be released and

6

serves as an auxiliary safety latch preventing the release of ejector 51 and the compression and jamming of the bag within the housing since latch bar 63 must first be released by the withdrawal of restraining pin 70. The latter necessitates the selective positioning of toggle 90a by the triggering action (above described) which must be previously effected by suitable control mechanism, namely the actuation of the pneumatically operated device 250.

It is to be noted that pneumatically operated device 250 in addition to triggering toggle 90a and setting the mechanism for the subsequent release of ejector restraining latch bar 63 also releases, substantially simultaneously, the cover retaining latch 100 by actuating arm 100a, Figs. 4, 5 and 8, fulcrumed at 100b but adapted to turn clockwise as a unit with latch 100, whereupon the entire latch 100 is moved as a unit to release member 16 (see phantom view Fig. 5).

The parallel linkage of the hose coupling assembly 15 to the front ring 20 is most clearly seen in Figs. 2 and 3. There, link 115 pivoted at 116 to front ring 20 and at 117 to hose coupling assembly 15 forms one link in the parallel linkage while cover 16 fulcrumed at 17 to front ring 20 and at 118 to hose coupling assembly 15 forms the other link.

Button 10a on the upper front surface of housing 10 operates a circuit make and break switch 110, Fig. 9 of the conventional toggle snap switch type through rocker arm 111 pivoted at 112. This button 10a is locked in off position when cover 16 is open by pressure exerted by a sliding mechanism 113 biased to the left, Fig. 9, by spring 114. Thus, although button 10a may be used to start and stop the motor fan unit while the cover 16 remains closed, the opening of cover 16 with the circuit closed releases slide 113 and causes inclined surface 96, Fig. 9, to actuate a lug 95 on switch button 10a and move rocker arm 111, Fig. 9, counter-clockwise thereby opening the toggle switch circuit, stopping the motor fan unit and otherwise deenergizing the unit.

The electrical and pneumatic control units are operatively interrelated. The pneumatic system comprises a pressure differential measuring control device 200, Figs. 8 and 9, having a lower casing 201, Figs. 4 and 5, and an upper casing 202 separated by a diaphragm. The space in the lower casing below the diaphragm is connected by communicating conduit 210, Figs. 4, etc., to opening 215, Fig. 2, on the dirty or dust collecting side of the dust bag; while the space in the upper casing above the diaphragm is connected by communicating conduit 220, Figs. 8, 9 T-shaped coupling 221 and common conduit 225 to opening 230, Figs. 4, 5, and especially 8, on the clean side of the dust bag. The remaining connection from the T-shaped coupling communicates by means of conduit 234, Fig. 8, with one side of valve 240 comprising valve stem 241 biased normally to closed position by a spring. When valve 240 is open it communicates high suction to the interior of pneumatically operating triggering device 250, comprising a lower casing 251, Fig. 4, sealed by diaphragm 252, Fig. 8, biased to distended or upward position by a spring and capable of actuating tripping mechanism through link member 254.

The electrical system for energizing the motor fan unit and the electrical controls is clearly shown in diagrammatic form in Fig. 9. Vacuum cleaner electrical cord 300 conveys current from the house lines at 110 volts to terminal strips 301

within the cleaner housing from which one line 302 goes to motor 303, the other line goes to motor 303 through a circuit including line 305 on-and-off switch 310, line 311 and line 313. The circuit for energizing the electrical controls comprises line 320, electromagnet 325, line 326, switch 327 of pressure differential pneumatic control unit 200, and line 328 to the house circuit through the cleaner cord 300. The switch 327 of pressure differential pneumatic control unit 200 includes a biasing spring which may also serve as a conducting element and for maintaining the switch normally open between the switch terminals.

In detail and particularly with respect to the operation of the pneumatic and electrical controls and referring especially to Fig. 9 where details of structure are illustrated the force exerted on the pressure differential membrane of switch 200 progressively increases with continued dust collection, until it attains sufficient value to actuate switching means 327 and complete a circuit by closing contacts therein and thereby energize electromagnet 325. The armature 350 of electromagnet 325 fulcrumed at 351 and biased by spring 352 to hold valve 240 closed, then opens valve 240 allowing high suction to operate diaphragm 252 which in turn through a series of linkages 254, 100a, 90c, etc., selectively positions toggle 90a so that the latter can subsequently by additionally imparted movement release latch pin 70, Figs. 4, 5, 6 and 8, which restrains latch bar 63 holding ejection plate 52 and also through lever 100a, Figs. 4, 5, 6 and 8, substantially simultaneously, trips cover releasing latch 100, Figs. 5 and 8 which holds cover assembly 16 closed against spring tension. The release of cover 16 first breaks a circuit at the contact points of switch 310, Fig. 9, through release of sliding mechanism 113 which is biased by spring 114 to throw switch 310 to off position, Figs. 2, 3, and especially 9, thereby deenergizing the motor fan unit. Thereafter the front cover continues to open and after opening substantially 90°, mechanical triggering mechanism comprising lever 90 withdraws latch pin 70 (see phantom view Fig. 6) releasing the bag ejector mechanism 51 through a previously traced series of steps, allowing the bag ejector plate 52, Figs. 2, 3 to push the bag forward and throw the bag and its contained dirt out of the cleaner casing.

The ejector plate 52 moves forward and outward when released until arrested by the extended length of flat spring 53, Fig. 2. The momentum of the moving dust-filled bag causes it to continue onward in its own trajectory out of the cleaner casing after which it comes to rest on the floor.

It is to be noted, that in order to effect the release of ejector plate 52 by the slipping of spring latch 62 under the bottom edge of depending lug 52b, a short forward travel of latch bar 63 is necessary. This motion is a result of pressure exerted by leaf or flat spring 53 following the withdrawal of pin 70 (see phantom view, Fig. 6) and the accompanying release of the forward end 63c of the latch bar 63. During this short forward travel, the inclined portion 63d of latch bar 63 actuates pin 70 from above to undergo still further downward travel and causes the upper spool end 70a of pin 70 to throw toggle 90a back into its normal position (full view, Fig. 6); see also Fig. 3 where the repositioning of toggle 90a is completed.

The reloading or repositioning of ejector

mechanism 51 so as to ready the cleaner for the insertion of a clean bag (see Fig. 3) is effected by pushing ejector plate 52 manually all the way back into the cleaner housing until lug 52b passes over and beyond the restraining edge of spring latch 62; then, by continuing the backward travel of ejector plate 52, depending lug 52b strikes upwardly extending portion 63b of latch bar 63 and the entire latch bar 63 is moved sufficiently far back so as to allow pin 70 (biased upwardly by pin spring 70b) to ride up the inclined surface 63d until the forward end 63c of latch bar 63 is securely held against pin 70 (see Fig. 3).

It is to be understood that the specific embodiment herein described in considerable detail is merely an illustrative embodiment of the invention which is to be limited in scope solely by the appended claims.

What I claim is:

- 20 1. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 25 2. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 30 3. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 35 4. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 40 5. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 45 6. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 50 7. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 55 8. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 60 9. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 65 10. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 70 11. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.
- 75 12. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.

13. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a selectively movable member settable to a position conditioning it for releasing said restraining means upon subsequent additional movement of said member, means responsive to the establishment of a predetermined pressure difference between the inside and outside of said bag for setting said selectively operable member to said above-mentioned position, means responsive substantially simultaneously with the setting of said selectively operable member for releasing said conduit securing means, and further means responsive to the further movement of said conduit for effecting the additional movement of said selectively operable member to release said restraining means.

duit for communicating with said aperture, releasable means for movably securing said conduit to said housing, means for ejecting said dust bag, restraining means for preventing operation of said bag ejecting means, a member selectively settable to a first position conditioning said member for releasing said restraining means upon subsequent additional movement of said member and settable to a second position to render it ineffective for said releasing operation upon said additional movement, means responsive to the establishment of a predetermined pressure difference between the inside and outside of said dust bag for setting said selectively operable member to said above-mentioned first position, means responsive substantially simultaneously with the setting of said selectively operable member for releasing said conduit securing means, and further means responsive to further movement of said conduit for effecting the additional movement of said selectively operable member to release said restraining means.

4. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a slidable restraining bar having a latch at one end and at the other end an inclined surface terminating in an abutment arrested by said restraining means, release of said abutment by said restraining means causing said inclined surface to subject the restraining means to still further movement, a selectively movable member settable to a position conditioning it for releasing said restraining means upon subsequent additional movement of said member, means responsive to the establishment of a predetermined pressure difference between the inside and outside of said dust bag for setting said selectively operable member to said above-mentioned position, means responsive substantially simultaneously with the setting of said selectively operable member for releasing said conduit securing means, further means responsive to the further movement of said conduit for effecting the additional movement of said selectively operable member to release said restraining means, and additional means responsive to said still further movement of said restraining means for setting said selectively positionable member to a position incapable of effecting the release of said restraining means.

5. In a vacuum cleaner, a housing enclosing a dust receptacle compartment, an opening in said compartment, a dust receptacle insertable into said compartment through said opening and being formed with an inlet aperture, an inlet conduit for communicating with said aperture, releasable means for movably securing said conduit to said housing, means for ejecting said dust bag, restraining means for preventing operation of said bag ejecting means, a movable restraining bar having a latch at one end and at the other end an inclined surface terminating in an abutment arrested by said restraining means, release of said abutment by movement of said restraining means causing said inclined surface to subject the restraining means to still further movement, a selectively movable toggle member settable to a position conditioning it for releasing said re-

straining means upon subsequent additional movement of said member, pneumatic means responsive to the establishment of a predetermined pressure difference between the inside and outside of said dust bag for setting said selectively operable toggle member to said above-mentioned position, means responsive substantially simultaneously with the setting of said selectively operable toggle member for releasing said conduit securing means, further means responsive to the further movement of said conduit for effecting the additional movement of said selectively operable toggle member to release said restraining means, and additional means responsive to said still further movement of said restraining means for setting said selectively positionable toggle member to a position incapable of effecting the release of said restraining means.

6. In a vacuum cleaner having a housing enclosing a dust receptacle compartment, an opening in said compartment, and a dust receptacle insertable into said compartment and ejectable from said compartment through said opening, the combination therewith comprising a member for ejecting said dust bag, a guide rod, means on said ejecting member slidable on said rod, a latching means releasably restraining said member from movement along said rod, means for moving said latching means, and means engaging said latching means and effective upon movement of the latter to release said latching means from said member to free the latter for movement along said rod.

7. In a vacuum cleaner having a housing enclosing a dust receptacle compartment, an opening in said compartment, and a dust receptacle insertable into said compartment and ejectable from said compartment through said opening, the combination therewith comprising a cover for said opening, a member for ejecting said dust receptacle, a guide rod, means on said ejecting member slidable on said rod, a latch bar having at one end coupling means releasably coupling said member from movement along said rod and at the other end latching means for restraining said bar in one position, means for moving said latch bar, means for uncoupling said coupling means upon movement of said latch bar, and means actuated by said cover and engaging said latching means and effective upon opening of said cover to release said latching means from said latch bar whereby movement of said latch bar frees said member for movement along said rod.

8. In a vacuum cleaner having a housing enclosing a dust receptacle compartment, an opening in said compartment, and a dust receptacle insertable into said compartment and ejectable from said compartment through said opening, the combination therewith comprising a movable member for ejecting said dust receptacle and a flat leaf spring having a fixed end attached to said housing and a movable end attached to said member for moving the latter upon expansion of said spring, the extent of travel of said movable member being determined by the length of said flat spring.

9. In a vacuum cleaner having a housing enclosing a dust receptacle compartment, an opening in said compartment, and a dust receptacle insertable into said compartment and ejectable from said compartment through said opening, the combination therewith comprising a cover for said opening, a member for ejecting said dust receptacle, means for restraining said member from

operation, a flat leaf spring having a fixed end attached to said housing and a movable end attached to said member for moving the latter upon expansion of said spring, and means actuated by said cover and engaging said restraining means and effective upon opening of said cover to release said restraining means, the extent of travel of said member being determined by the length of said flat spring.

10. In a vacuum cleaner, a housing enclosing a dust receptacle compartment, an opening in said compartment, a dust receptacle insertable into said compartment through said opening and being formed with an inlet aperture, an inlet conduit for communicating with said aperture releasable means for movably securing said conduit to said housing, means for ejecting said dust bag, restraining means for preventing operation of said bag ejecting means, a selectively movable toggle member settable to a position conditioning it for releasing said restraining means upon

10
15

subsequent additional movement of said toggle member, pneumatic means responsive to the establishment of a predetermined pressure difference between the inside and outside of said dust bag for setting said selectively operable toggle member to said above-mentioned position, means responsive substantially simultaneously with the setting of said selectively operable toggle member for releasing said conduit securing means, and further means responsive to the substantial movement of said conduit for effecting the additional movement of said selectively operable toggle member to release said restraining means.

LEON P. BORKOSKI.
